UNITED STATES PATENT OFFICE.

OLLIE A. KARHU, OF GREYBULL, WYOMING.

BOX OPENER.

Application filed April 22, 1924. Serial No. 708,212.

To all whom it may concern:

Be it known that I, OLLIE A. KARHU, a citizen of the United States, residing at Greybull, in the county of Big Horn and State of Wyoming, have invented certain new and useful Improvements in a Box Opener, of which the following is a specification.

My invention relates broadly to hand tools and more particularly to a box opener.

An object of my invention is to provide a box opening tool which is effective both upon heavy cardboard boxes and wooden receptacles to enable the boxes to be readily and rapidly opened.

Another object of my invention is to provide a combination hand tool having means for withdrawing nails from wooden boxes and having a cutter for severing wire nails where such becomes necessary, cooperating with the parts of the tool for providing the desired amount of leverage in ripping open the box.

Another object of my invention is to provide a tool for opening boxes which may be gripped in one hand and parts moved together to grip portions of the box to be opened and then the entire tool moved in the manner of a lever for ripping open the box.

Still another object of my invention is to provide a hand tool consisting of a pair of substantially similar portions one of which is slidably mounted within the other for engaging both the upper and lower surfaces of the portions of the box to be opened to provide an effective grip upon the box.

My invention will be more fully understood by reference to the accompanying drawings in which:

Figure 1 is a partial perspective view of a wooden box showing my box opener in position at one corner of the box in the process of removing a portion of the cover from the box; Fig. 2 is a front elevation of my box opener having a portion shown in longitudinal cross section to more clearly illustrate the cooperation of the parts; Fig. 3 is an end view showing my box opener in position for breaking open a corrugated cardboard box; and Fig. 4 is a plan view showing the arrangement of the several parts of the box opener.

Referring more particularly to the drawings, reference character 1 represents a wooden box on which my tool is intended to

operate. The tool comprises a pair of substantially rectangular strip members closed at one side by a handle portion. One of the strip-like members is indicated by reference character 2 with upwardly extending side members 3 and 4. The portion 2 extends on either side of the upstanding portions 3 and 4 but further in one direction than the other. A handle 8 is positioned between the extremities of the side portions 3 and 4 and secured thereto as indicated at 10 and 9 respectively. The second portion of the box opener is of substantially the same contour as the first portion consisting of flat plate member 5 and upwardly extending vertical side members 6 and 7 joined at their extremities by a handle member 20 riveted as indicated at 21 and 22. The side members 6 and 7 are slotted as represented at 18 and 19 to enable the flat portion 5 to move toward or away from the flat portion 2. Hook members 11 and 12 are provided adjacent the extremities of side members 3 and 4 permitting coil springs 16 and 17 to be interposed between pin members 14 and 15 on the second portion of the box opening tool carried by side members 6 and 7 adjacent the lower surface 5. The side members 3 and 4 are slotted as represented at 26 in such manner that pins 14 and 15 are free to ride vertically in the slots. The flat plate member 2 extends substantially beyond the flat plate member 5 and each is provided with gripping teeth directed toward each other to enable the members 2 and 5 to substantially grip both the top and bottom surface of the portion of the box to be opened. The flat portion 2 of the box opening tool is provided with nail removing means 23 and the side members 3 and 6 cooperate to form a nail cutting device as represented by opening 27. That is to say there are two openings 27 one in side member 3 and another in side member 6 which when registered with each other permit the wire nail which is to be cut to be inserted therein and when one portion of the tool is moved with relation to the other portion the cutting surfaces of apertures 27 move in such manner as to cut wire or nails which may be inserted between the cutting surfaces.

In the operation of my box opening tool, the flat surface 2, which is provided with a bladed edge 28, is driven under the surface 110 of one portion of the box using the edge 29 as a driving face. The handles 8 and 20 are

firmly grasped and drawn together operating to move the flat plate members 2 and 5 together and gripping a portion of the box. In Figure 1 this action is represented as applied to a wooden box while in Figure 2 the action has been shown in connection with a paper box. The tool may then be drawn in an angular direction operating as a lever to rip open the box. By loosening the handle members, springs 16 and 17 immediately increase the space between the flat plates 2 and 5 and enable the box opener to be moved to another position along the box and the box cover again operated upon.

15 While I have described the invention in a certain particular embodiment I desire that it be understood that modifications may be made and that I intend no limitations upon the invention other than are imposed by the 20 scope of the appended claims.

What I claim and desire to secure by Letters Patent of the United States is as follows:

1. A box opening tool, comprising in combination a pair of substantially similar rectangular members each having a hand grip at one side and one adapted to slide within the other, each of said members having a flat plate on one side thereof, said plates being 25 adapted to fit on the top and bottom of a portion of a box cover to be removed, said flat plates being normally spaced apart under spring tension and adapted to grip said box cover when said hand grips are moved together.

2. A box opening tool, comprising in combination a pair of substantially rectangular strip like members each having a hand grip at one side thereof and one of said members being adapted to slide within the other of said members, each of said members carrying a flat plate member at an end opposite the hand grip and resilient means for

normally holding said plate members spaced apart whereby said plate members may be 45 moved together when said hand grips are drawn together.

3. A box opening tool, comprising in combination a pair of members slidable one within the other, each of said members comprising a flat plate and a pair of upstanding side members, a hand grip connected between the upper extremities of each of said side members, one pair of said side members being provided with slots adjacent the lower ends thereof and the other pair of side members being provided with slots adjacent the upper extremities thereof, pins connected to one pair of said side members and spring means interposed between said pins and the upper extremities of the other pair of side members whereby said flat plate members may be moved together against the action of said spring means by drawing said hand grips together.

4. A box opening tool, comprising in combination a pair of substantially rectangular strip-like members each having a hand grip at one side thereof and one of said members being adapted to slide within the other of 70 said members, each of said members carrying a flat plate member at an end opposite each hand grip, one of said flat plate members extending on either side of the other of said flat plate members and having a 75 bladed edge and a hammer edge opposite thereto, and resilient means for normally holding said plate members spaced apart whereby said plate members may be moved together when said hand grips are drawn 80 together and said extended flat plate member driven under a box cover in the process of opening the box.

In testimony whereof I affix my signature,

OLLIE A. KARHU.
